UNITED STATES PATENT OFFICE.

JOHN C. CARPENTER, OF HOUSTON HEIGHTS, TEXAS.

CARBURETER.

1,153,999.

Specification of Letters Patent. Patented Sept. 21, 1915.

Application filed April 1, 1912. Serial No. 637,355.

To all whom it may concern:

Be it known that I, JOHN C. CARPENTER, a citizen of the United States, residing at Houston Heights, in the county of Harris 5 and State of Texas, have invented certain new and useful Improvements in Carbureters, of which the following is a specification.

My invention relates to new and useful 10 improvements in vaporizing and carbureting devices, and more particularly to that class of such devices which are designed to be used on internal combustion engines.

My invention is intended to provide a device 15 which, without the use of a fuel reservoir and float-controlled valve therein, will deliver to the engine, at all times, a proper mixture of liquid fuel and air, the liquid fuel being atomized or nebulized, and each 20 molecule of liquid fuel being closely surrounded by the correct number of oxygen molecules. As the fineness of division of the liquid fuel, by means of the spray nozzle, is due to the velocity of effluxion from 25 the fuel nozzle, and the velocity of effluxion due, in turn, to the difference in pressures existing at the two ends of the fuel passage, it is obvious that the fuel must leave the nozzle, at best, as a thin conical sheet of 30 liquid, and more often in a solid stream or in globules. Observation through a glass carbureting chamber has shown this to be true. To overcome this objectionable condition, and to more effectively divide the 35 particles of fuel, I provide means for mechanically disintegrating the fuel as it is discharged into the air stream. This is accomplished by means of a column of air, induced by the suction of the engine, rotating 40 bodily about the spray nozzle, the liquid fuel being drawn through its passage by the motor simultaneously with the influx of the air with which it mixes. The rotating column 45 of air causes the fuel to rotate as it leaves the nozzle, the centrifugal force thereby exerted causing the cone of fuel to spread out, allowing a more intimate mingling of the fuel and air and greatly assisting vaporization. The finer fuel divisions are caught up and 50 entrained in the rotating air column, while the heavier fuel particles, yielding to a greater centrifugal force, are thrown against the walls of the carbureting chamber, where they are held by inwardly projecting flanges 55 until further vaporized. A mushroom deflector is provided on the needle valve and a

deflector cone supported in the carbureting chamber, which more widely separate the fuel particles, allowing greater opportunity for surface vaporization. The mixture is 60 then drawn through a plurality of relatively small flues, mounted in a flue plate, and presenting a large area for surface vaporization. Auxiliary air is admitted among the flues, through suitable ports in the casing, 65 and is therefore intimately mingled with the gaseous mixture.

With the above and other objects in view, my invention has particular relation to certain novel features of construction and operation, an example of which is described in this specification and illustrated in the accompanying drawings, wherein:

Figure 1 is a vertical sectional view of my entire device. Fig. 2 is a plan view of the 75 lower plate, with its coöperating air valves.

Referring now, more particularly, to the drawings, wherein like numerals of reference designate similar parts in each of the figures, the numeral 1 refers to a circular 80 bottom plate, provided with six segmental ports 2 for the primary air passage 3, and six segmental ports 4 for the secondary air passage 5. Mounted concentrically on said plate 1 is the fuel standpipe 6, having a 85 flared nozzle 7, and carrying six spiral baffles 8 spanning the primary air passage 3, the said plate 1, standpipe 6 and baffles 8 being integral.

The numeral 9 refers to the primary air 90 casing, which incloses the fuel standpipe and rests against the outer edges of the baffles 8 and upon the plate 1. The casing 9 is also provided with six spiral baffles 10, 95 spanning the secondary air passage 5, the casing 9 and the spiral baffles 10 being integral.

The numeral 11 refers to the secondary air 100 casing, which rests against the outer edges of the spiral baffles 10, and upon the plate 1, 105 and extends upward so as to form the carbureting chamber 12 and support a flue plate 13. The casing 11 is in the form of a Venturi tube, the upper portion inclosing the carbureting chamber 12, being provided with inwardly extending spiral flanges 14. Mounted in the flue plate 13 are a plurality 110 of flues 16, with their upper ends free and their lower ends projecting through said flue plate and curved concentrically anti-clockwise so as to meet and receive the mixture rotating clockwise in said carbureting

chamber 12. The flues 16 extend upward into a mixing chamber 17, inclosed by a casing 18, having a plurality of circumferential ports 19 for the admission of auxiliary air. The ports 19 are controlled by an annular valve 20, operated by lever 21.

Mounted above the flues 16, in the casing 18, is a butterfly throttle valve 22, operated by lever 23, and provided with a perpendicular depending projection 24. Hingedly connected to said projection 24 is a rod 25, which engages a slot 26 in the stem 27 of a fuel valve 28. This fuel valve normally rests in the nozzle 7 and obstructs the flow of fuel, and is provided with a mushroom deflector 29.

Surrounding the valve stem 27 and supported by the flue plate 13 is a deflector in the form of a cone frustum, designated by 20 the numeral 30.

Concentrically mounted on said fuel standpipe 6, and resting against the bottom of plate 1, is a circular primary air valve 31, operated by lever 32, and controlling the 25 primary air ports 2. Primary air valve 31 is held against the plate 1 by a nut 33 and a locknut 34.

The numeral 35 refers to a circular secondary air valve, operated by the lever 36, 30 and controlling the secondary air ports 4. The secondary air valve 35 is held in contact with the bottom of plate 1 by the overlapping edge of the primary air valve 31.

The circular bottom plate 1, the casing 11, 35 the flue plate 13 and the casing 18 are held together by through bolts 37, which screw into the plate 1.

No showing is made of means for operating either of the three air valves. The 40 primary air valve may be under the control of the operator, while the secondary and auxiliary air valves may be interconnected by a lever, and this lever under the control of another lever which is operated by a governor and the throttle rod, and therefore responsive to both speed and load. The auxiliary valve in this case would be held closed by a spring until the secondary air valve was fully open. Means for operating 45 these valves are illustrated and described in my application No. 489,982, filed April 15, 1909.

The operation of this device is described as follows: Before attempting to start the 50 engine the primary air valve is nearly closed. The fuel valve and the secondary and auxiliary air valves are normally closed while the engine is at rest. The engine suction induces a pressure reduction about the nozzle, which causes air to enter through the 55 primary air ports 2 and lift the fuel valve 28, allowing fuel to issue. It will be seen that the fuel valve is lifted by suction, and held down and regulated by the throttle 60 valve, through the rod 25 engaging in the

slot 26 of the stem 27 of the fuel valve 28. As the throttle valve is opened farther, the fuel valve is allowed to lift higher. As the air passes upward through the primary air 70 passage 3, body rotation is imparted to it by means of the spiral baffles 8. This body rotation of the air column should not be confused with the spiral motion imparted by carburetors having but one spiral spanning the air passage, or even a plurality of 75 spirals not extending across the air passage.

A single spiral produces a single column of air spiraling about a given point or axis. When a spiraling column of air passes a fuel nozzle, the fuel is drawn to one side, 80 and centrifugal force is not exerted thereon as it leaves the nozzle, in such a manner as to produce a whirling fuel spray. In the device illustrated herein, it will be noted that the spirals end a short distance below 85

the nozzle, so that the six spiraling columns of air, directed upward by the six spiral baffles 8, merge into a single column before reaching the fuel nozzle, thus producing a single column of air rotating bodily about 90

the nozzle, and exerting equable centrifugal force at all radii of the fuel nozzle upon the fuel ejected from said nozzle. Body rotation is imparted to the secondary air, by 95

means of the spiral baffles 10, their effect 100 being similar to that of the spiral baffles 8 upon the primary air. The secondary air is called into action as soon as the engine begins to rotate, and supplements the action

of the primary air upon the fuel. The auxiliary air is called into use only after the secondary air valve is fully open. As the fuel standpipe, the primary air passage and the secondary air passage are concentric, the primary and secondary air columns will 105 combine as they pass the nozzle. As the fuel valve projects into the nozzle and forms an annulus of the fuel therein, it will be seen that the rotating air column will impart rotation to the annulus of fuel ejected from the nozzle, and this will be deflected by the mushroom deflector 29, spreading over the surface thereof and affording opportunity for surface vaporization. The lighter particles of fuel will be entrained in 110

the air column passing the mushroom deflector, while the heavier particles of fuel will be thrown outwardly by centrifugal force against the walls of the carbureting chamber, where they will be held by the projecting flanges until vaporization has so far progressed that the lighter particles will be entrained in the rotating column. As the 115 rotating column passes upward between the frusto-conical deflector 30 and the diverging walls of the casing 11, it rotates in increasing circles, and comes in contact with a greater evaporating surface. Whenever a particle of fuel comes in contact with any portion of the carbureting chamber, it is 120

125

130

135

spread out and exposed to a greater number of molecules of oxygen. Since the deflector 30 is supported by the flue plate 13 and is spaced therefrom, the lighter particles will be drawn over the edge of said deflector and through the flues nearest the center of said flue plate, while the heavier particles will be received by the outer flues and the unvaporized portion discharged against the converging sides of the casing 18. These flues are concentrically curved so as to receive the rotating mixture from the carbureting chamber, and are supported at the lower end only, so that auxiliary air may be admitted among the flues by means of the annular valve 20, the whole mixture passing from the mixing chamber to the engine in a more homogeneous mass than is possible without the use of the flues. Air valves 20, 31 and 35 rotate about their axes to open and close their respective ports.

Having thus described my invention, I desire to claim, by Letters Patent, the following:

1. In a device of the character described, the combination with a fuel duct; of a plurality of air passages concentric with said fuel duct; a carbureting chamber, adjacent to said fuel duct and air passages, and arranged to receive fuel and air, respectively, therefrom; and a flange projecting inwardly from the wall of said carbureting chamber.

2. In a device of the character described, the combination with a fuel duct; of a plurality of air passages, each surrounding said fuel duct; a carbureting chamber, adjacent to said fuel duct and air passages, and arranged to receive fuel and air, respectively, therefrom; and a flange projecting inwardly from the wall of said carbureting chamber.

3. In a device of the character described, the combination with a carbureting chamber; of an air passage arranged to discharge into said carbureting chamber; a fuel nozzle mounted in said air passage and arranged to discharge into said carbureting chamber; a plurality of spiral partitions spanning said air passage and arranged to impart rotation bodily to the air passing said fuel nozzle; and a flange projecting inwardly from the wall of said carbureting chamber.

4. In a device of the character described, the combination with an air passage; of a fuel nozzle mounted therein; a flared carbureting chamber, having its smaller end adjacent to said air passage and fuel nozzle and arranged to receive air and fuel, respectively, therefrom; and a flange projecting inwardly from the wall of said carbureting chamber and forming therewith a receptacle for receiving the heavier fuel particles.

5. In a device of the character described, the combination with an air passage; of a fuel nozzle mounted therein; a flared carbureting chamber, having its smaller end adja-

cent to said air passage and fuel nozzle, and arranged to receive air and fuel, respectively, therefrom; a means for bodily rotating said air column about said fuel nozzle so that the fuel discharged from said nozzle shall be subjected to centrifugal force and discharged from said nozzle in a diverging spray; and a means provided upon the wall of said carbureting chamber for receiving the heavier particles of fuel spray and retaining the same until they are further vaporized.

6. In a device of the character described, the combination with an air passage; of a fuel nozzle mounted therein; a flared carbureting chamber, having its smaller end adjacent to said air passage and fuel nozzle and arranged to receive air and fuel, respectively, therefrom; a flange projecting inwardly from the wall of said carbureting chamber and forming therewith a receptacle for receiving the heavier fuel particles; and a spray deflector in said carbureting chamber, adjacent to said fuel nozzle, and adapted to deflect the said fuel spray toward said receptacle.

7. In a device of the character described, the combination with an air passage; of a fuel nozzle mounted therein; a flared carbureting chamber, having its smaller end adjacent to said air passage and fuel nozzle and arranged to receive air and fuel, respectively, therefrom; a flange projecting inwardly from the wall of said carbureting chamber and forming therewith a receptacle for receiving the heavier fuel particles; a spray deflector in said carbureting chamber, adjacent to said fuel nozzle, and adapted to deflect the fuel spray toward said receptacles; and a needle fuel valve, carried by said deflector and coöperating with said fuel nozzle to open and close the same, and adapted to divide the fuel in said nozzle so as to form an annulus of fuel around said fuel valve.

8. In a device of the character described, the combination with a fuel duct; of a primary air duct; an auxiliary air duct; a passage leading from said ducts to an engine; a flue plate within said passage and between said primary air duct and said auxiliary air duct; a plurality of flues, mounted at one end upon said flue plate and having their other ends free, said fuel duct and primary air duct discharging through said flues and said auxiliary air duct discharging among said flues.

9. In a device of the character described, the combination with a fuel duct; of a primary air duct; an auxiliary air duct; a passage leading from said ducts to an engine; a flue support within said passage and between said primary air duct and said auxiliary air duct; a plurality of flues, mounted at one end upon said flue support

and having their other ends free, said fuel duct and primary air duct discharging through said flues and said auxiliary air duct discharging among said flues and into 5 said passage.

10. In a device of the character described, the combination with a fuel nozzle; of a primary air passage; an auxiliary air passage; a carbureting chamber receiving from 10 said fuel nozzle and primary air passage; a mixing chamber receiving from said carbureting chamber and auxiliary air passage; a flue plate separating said carbureting and mixing chambers; and a plurality 15 of flues mounted at one end in said flue plate and having their other ends free, and extending into said mixing chamber.

11. In a device of the character described, the combination with a fuel nozzle; of a 20 primary air passage; an auxiliary air passage; a carbureting chamber receiving from said fuel nozzle and primary air passage; a mixing chamber receiving from said carbureting chamber and auxiliary air passage; a flue plate separating said carbureting 25 and mixing chambers; and a plurality of flues, each having one end free and the other projecting through said flue plate into said carbureting chamber, and having their 30 projecting ends inclined so as to meet the fluid discharged from said carbureting chamber and readily receive the same.

12. In a device of the character described, the combination with a fuel nozzle; of a 35 primary air passage; an auxiliary air passage; a carbureting chamber receiving from said fuel nozzle and primary air passage; a mixing chamber receiving from said carbureting chamber and auxiliary air passage; a flue plate separating said carbureting 40 and mixing chambers; and a plurality of flues; mounted at one end in said flue plate and having their other ends free, and

having their mounted ends projecting through said flue plate and curved concentrically with said carbureting chamber. 45

13. In a device of the character described, the combination with a fuel nozzle; of a primary air passage; an auxiliary air passage; a flue plate separating the element, 50 produced by the combination of the fluids discharged through said fuel nozzle and primary air passage, from the element discharged through said auxiliary air passage; and a plurality of flues mounted at one end 55 in said flue plate and having their other ends free, said flues being so arranged as to commingle said elements, one of said elements being admitted among said flues and the other of said elements being conducted 60 through said flues.

14. In a device of the character described, the combination with a fuel nozzle; of a primary air passage; an auxiliary air passage; a means within said primary air passage for producing a whirling fuel spray; a carbureting chamber receiving from said fuel nozzle and primary air passage; a mixing chamber receiving from said carbureting chamber and auxiliary air passage; a 70 flue plate separating said carbureting and mixing chambers; and a plurality of flues, each having one end projecting through said flue support into said carbureting chamber and inclined so as to meet the whirling 75 fuel spray and readily receive the same, and having the other end free and projecting into said mixing chamber.

In testimony whereof I have signed my name to this specification in the presence of 80 two subscribing witnesses.

JOHN C. CARPENTER.
